United States Patent Office.

J. W. LARIMORE, OF CHICAGO, ILLINOIS, ASSIGNOR TO HIMSELF AND ALONZO MARKS, OF SAME PLACE,

Letters Patent No. 96,121, dated October 26, 1869; antedated October 12, 1869.

IMPROVEMENT IN SIGNS FOR STREET-LAMPS.

The Schedule referred to in these Letters Patent and making part of the same.

To all whom it may concern:

Be it known that I, J. W. LARIMORE, of the city of Chicago, in the county of Cook, and State of Illinois, have invented certain new and useful Improvements in the Construction and Arrangement of Signs on Street-Lamps; and I do hereby declare that the following is a full and exact description thereof, reference being had to the accompanying drawings, forming part of this specification, and to the letters of reference marked thereon.

The object of my invention is to provide a simple, cheap, and novel means, whereby the names of streets, in a city or town, may be plainly indicated at night on lamps placed at the intersection of streets, in a more perfect manner than has hitherto been effected by any device heretofore used for that purpose.

The nature of my invention consists in the use or employment of four sheet-metal plates of suitable dimensions, fastened together at their ends in such a manner as to form a square frame, on which the names of the streets are painted. This frame is made to slide over the top of the lamp, and fixed thereon by means of springs or other suitable fastenings with which it is provided, and each of its four sides is thrown forward at an angle of about thirty degrees, or other suitable degree of inclination, so that the rays of light emitted from the jet within the lamp are thrown on the surfaces of its four sides, on which the names of the streets are painted, by which means the names of the streets are made distinctly legible at a considerable distance.

To enable others skilled in the art to make and use my invention, I will proceed to describe it.

Figure I is a side elevation of a lamp with my improved device attached thereto.

Figure II is a top plan view of the same.

Letters of like name and kind indicate like parts in each of the figures.

A is an ordinary street-lamp, constructed in the usual manner.

B is the frame, on which the names of the streets are painted.

This frame is made of any of the sheet-metals or

other materials adapted for the purpose, and is made to fit on the top of the lamp A, to which it is attached by means of any suitable springs or fastenings, D D, so as to be secured in the desired position, and is so constructed that the outer surfaces of its four sides, on which the names of the streets are painted, shall be inclined from the perpendicular at an angle of thirty degrees, more or less, so as to receive the rays of light emitted from the flame C, so that, by the strong light thus cast upon the said surfaces, the names painted thereon are distinctly visible, and plainly and readily indicated to persons passing along the streets.

The advantages of this invention are obvious, for the reason that the strong light thrown upon the names painted on the several surfaces of the frame renders them more distinct and legible than has been accomplished by any other device hitherto used, thus making it an invention of great public utility, while, at the same time, it is simple and inexpensive in its construction.

I am aware that various methods have been devised for the purpose of indicating the names of streets at night; among them, those that are transparent by night and opaque by day; but I am not aware that signs have been constructed and arranged so as to throw the light upon the letters on a sign, secured by means of springs, as set forth in my invention. And it may be observed that the eye is not dazzled by the light while reading the name, when arranged as herein described.

Having thus described my invention,

What I claim as new, and desire to secure by Letters Patent of the United States, is as follows:

The arrangement of the frame B, on which the names of the streets are painted, inclined forward at a suitable angle, and provided with the springs or other fastenings D D, in connection with an ordinary street-lamp, A, substantially as herein shown and described, and for the purposes set forth.

J. W. LARIMORE.
